UNITED STATES PATENT OFFICE.

ARTHUR C. SHEPARD, OF SEBRING, OHIO, ASSIGNOR TO AMERICAN DRESSLER
TUNNEL KILNS, INC., OF NEW YORK, N. Y., A CORPORATION OF NEW YORK.

TUNNEL-KILN.

1,366,424.

Specification of Letters Patent. Patented Jan. 25, 1921.

Application filed January 26, 1920. Serial No. 354,137.

To all whom it may concern:

Be it known that I, ARTHUR C. SHEPARD, a citizen of the United States, and a resident of Sebring, in the county of Mahoning and State of Ohio, have invented certain new and useful Improvements in Tunnel-Kilns, of which the following is a specification.

My present invention relates to tunnel kilns in which a high temperature zone is maintained in the kilns at a distance from the head or entrance end of the kiln, and in which the portion of the kiln between the high temperature zone and the entrance end forms a heating up zone through which the temperature varies more or less gradually from one end to the other. In such a kiln as the goods are moved slowly through the kiln from its entrance end to and through the high temperature zone, the goods are gradually brought up to the high temperature prevailing in the high temperature zone.

The object of the present invention is to provide simple and effective means whereby the temperature graduation in the heating up zone of the kiln is controlled, and my invention preferably comprises means whereby the temperature in the heating up zone of the kiln may be adjusted to meet different operating conditions.

My present invention was primarily devised as improvement on the well-known Dressler tunnel kiln in which the high temperature zone of the kiln is heated by the combustion of gas in combustion chambers located within the kiln at the high temperature zone thereof, and in which products of combustion are withdrawn from the combustion chambers proper through conduit extensions thereof passing through the heating up zone of the kiln to a point adjacent the head end of the kiln where these conduits are connected to some draft creating device such as an exhaust fan or stack. In this type of kiln the heat remaining in the products of combustion leaving the combustion chamber proper is to a large extent radiated from the walls of the conduits connecting the combustion chambers to the draft creating device, and the heat thus radiated is absorbed by the goods passing through the heating up zone of the kiln. In this type of kiln there is often a tendency for the mouth of the oven to be too hot, so

that the cold goods will be raised too rapidly in temperature on entering it. To avoid this too rapid heating of the goods, very undesirable with certain classes of goods, it has been the practice to make the heating up zone longer than would be otherwise necessary to retard the rapid heating up of the goods or to place a long ante chamber in front of the kiln chamber proper, and a specific object of the present invention is to provide simple and effective means whereby the slow and gradual heating up of the goods may be obtained with a heating up zone of shorter length than has heretofore been employed. To accomplish this I provide simple and effective means whereby a portion only of the gaseous products of combustion are utilized in treating the goods in the heating up zone of the kiln.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of my invention.

Of the drawings:

Figure 1 is a plan with the kiln wall in section of a portion of a tunnel kiln provided with my present invention;

Fig. 2 is an elevation in section on the line 2—2 of Fig. 1;

Fig. 3 is a section on the broken line 3—3 of Fig. 1;

Fig. 4 is a partial section on the line 4—4 of Fig. 1;

Fig. 5 is a view taken similarly to Fig. 1 illustrating a modification; and

Fig. 6 is a section on the line 6—6 of Fig. 5.

In the drawings I have illustrated the application of my invention to a tunnel kiln of the well-known Dressler type. In the kiln shown, A represents the kiln chamber proper, and B the ante chamber at the entrance or head end of the kiln. Track rails C are provided at the bottom of the chamber for the goods carrying cars N, and benches D are provided at the sides of the track on which are mounted the combustion chambers E. These benches also serve to protect

the goods carrying cars and the truck upon which they run from the high temperatures prevailing above the benches.

- Each of the two combustion chambers E located one at each side of the kiln is formed as shown of sections built up out of hollow tile as is usually the custom in Dressler kilns. The end of each combustion chamber E adjacent the entrance end of the kiln is connected to a junction box F ordinarily formed of cast iron and provided with a flange F' at one side projecting into the adjacent end of the combustion chamber. To the opposite side of each junction box F are connected the ends of a series of pipes G usually formed of iron. These pipes receive products of combustion from the corresponding combustion chamber E through the hollow interior of the junction box F.
- At the entrance end of the kiln, the group of pipes G are connected into a header or expansion box H. Preferably each junction box F is cemented to the corresponding combustion chamber and like the latter rests on sand or the like interposed between it and the bench D so that it can move longitudinally of the kiln on the supporting bench D as the relative dimensions of the parts change with variations in temperature.
- Preferably also each header H is anchored to the bench D on which it rests and stuffing box connections which may be packed with asbestos packing are provided between the tubes G and the headers H.
- Each header H is formed with an aperture in its underside which registers with a vertical channel I formed in the corresponding bench D. Each channel I is connected at its lower end with a conduit or channel I' leading to a suitable device, such as the stack J, for creating the necessary draft to draw off the products of combustion. Each junction box F is also formed with an aperture F' in its underside which communicates with the upper end of a vertical passage K formed in the corresponding bench D. The apertures F' and passages K are so proportioned and arranged that ample communication will not be interfered with as the parts expand and contract. Longitudinally disposed in each bench is a conduit or channel L which communicates at one end with the corresponding vertical channel K and at its opposite end with the corresponding vertical channel I. Each channel L thus serves as a bypass about the tubes G through which products of combustion may pass from the corresponding combustion chamber to the outlet conduit I'. To regulate the relative amounts of products of combustion passing through each group of pipes G and through the corresponding bypass channel L, I employ dampers M and M', by which the vertical passages K and I respectively may be throttled more or less.

As shown, the damper M comprises a body of refractory material which is mounted to slide in a guideway D' formed in the masonry work of the bench and extending into the latter from the adjacent outer wall of the kiln. Each damper M is provided with an operating handle or extension m extending to the exterior of the kiln. To facilitate inspection, adjustment and repair, a tunnel D² is shown as formed beneath the guideway D' and is normally closed at its outer end by a removable door D². The dampers M' may be constructed and arranged as are the dampers M and are each shown as provided with an operating handle m. Advantageously the channel L is formed of tubular tile section embedded in the concrete which forms the core or body portion of the benches D. Preferably these tile sections are slit longitudinally as indicated at L'. These slits and the joints between the adjacent sections of the tile eliminate expansion difficulties which would be experienced if such joints were not provided.

With the construction illustrated in Figs. 1 to 4 the thermal conditions in the heating up zone of the kiln depend upon the setting of the dampers M and M' and the consequent portion of the products of combustion leaving each combustion chamber which are passed through the corresponding group of tubes G located in the heating up zone of the kiln. By changing the setting of the dampers M and M', the ratio between the portion of the products of combustion passing through each group of tubes G and the remainder of the products of combustion passing through the corresponding channel L may be varied and the thermal conditions in the heating up zone correspondingly varied to suit operating conditions. It will be understood, of course, that with the channels L embedded in masonry as shown, the thermal conditions in the heating up zone of the kiln are not directly affected to any appreciable extent by the temperature or quantity of gases passing through the insulated channels L.

In the modified construction illustrated in Figs. 5 and 6 the escape conduit IA leading directly to the stack, or other device for removing the products of combustion, is located directly beneath the vertical channels KA which communicate at their upper ends with the openings in the underside of the corresponding junction boxes F and communicate latterly with the longitudinal channels LA in the benches D. Each channel LA, which may be formed like the channels L, described above, communicates at the extreme end of the kiln through a vertical passage LI¹⁰ with the interior of the expansion box or header H. With the construction shown in Figs. 5 and 6, communication between the upper end of each ver-

tical channel KA and corresponding junction box F is regulated by the damper M¹⁹, and communication between the lower end of the channel KA and the outlet conduit 5 IA is regulated by an adjustable damper M¹⁵. Communication between the expansion box or header H at the adjacent end of the corresponding channel LA is regulated by an adjustable damper M²⁰.

10 The arrangement shown in Figs. 5 and 6 differs from that shown in Figs. 1 to 4 in that the products of combustion which pass through each group of tubes G also passes through the channel LA in the bench beneath the tubes, but in this construction as in that first described a regulable portion only of the products of combustion passes through the tubes G in the heating up zone of the kiln, and the remainder of the products of combustion pass to the stack or other exhausting device without influence on the temperature of the heating up zone of the kiln. In the construction shown in Figs. 5 and 6 the by-pass by means of which a portion of the products of combustion are diverted away from the pipes G passing through the heating up zone is formed by the vertical channels KA.

With the construction shown in Figs. 5 and 6, the temperature normally prevailing in the channels LA will be less than that normally prevailing in the channels L of a kiln chamber of similar capacity and use constructed in accordance with Figs. 1 to 4. This lower temperature of the masonry embedded conduits is of some advantage, though ordinarily no difficulty will arise on account of the temperature of the gases passing through the conduits L shown in Figs. 1 to 4.

While in accordance with the provisions of the statutes I have illustrated and described the best form of embodiment in my invention now known to me, it will be apparent to those skilled in the art that changes may be made in the form of apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. A tunnel kiln with longitudinally extending masonry benches at the sides of a pathway at the bottom of the kiln for goods carrying means and having mounted on each of said benches an elongated combustion chamber, pipes connected to and forming an extension of said combustion chamber, and a header to which the ends of the pipes remote from said combustion cham-

ber are connected, each bench being formed with a channel having uprising end portions which communicate one with the interior of said header and the other with the interior of the combustion chamber at the opposite ends of said pipes and with an outlet from said channel for products of combustion, and dampers regulating the relative amounts of products of combustion passing from the combustion chamber to said outlet through said pipes and a portion of said channel, and through the by-pass about said pipes formed by the remaining portion of said channel.

2. A tunnel kiln formed with longitudinally extending masonry benches at the sides of a pathway at the bottom of the kiln for goods carrying means and having mounted on each of said benches a combustion chamber formed of refractory material, metallic pipes connected to and forming an extension of said combustion chamber, a junction box connecting said pipes to said combustion chamber and a header to which the ends of the pipes remote from said combustion chamber are connected, said junction boxes and headers being formed each with an opening through its bottom wall, each bench being formed with a channel having uprising end portions communicating one with the opening in the bottom of the corresponding junction box and the other with the opening in the corresponding header, and with an outlet for products of combustion communicating with said channel, and dampers regulating the relative amounts of products of combustion passing from each combustion chamber to the corresponding outlet through said pipes and one portion of said channel and through the by-pass about said pipes formed by the remaining portion of said channel.

3. A tunnel kiln with longitudinally extending masonry benches at the sides of a pathway at the bottom of the kiln for goods carrying means and having mounted on each of said benches an elongated combustion chamber, pipes connected to and forming an extension of said combustion chamber, and a header to which the ends of the pipes remote from said combustion chamber are connected, each bench being formed with a channel having uprising end portions which communicate one with the interior of said header and the other with the interior of the combustion chamber at the opposite ends of said pipes and with an outlet from said channel for products of combustion, and dampers regulating the relative amounts of products of combustion passing from the combustion chamber to said outlet through said pipes and a portion of said channel and through the by-pass about said pipes formed by the remaining portion of said channel.

- channel, the body portion of each of said channels being formed of tubular tile sections jointed together and embedded in concrete.
- 5 4. A tunnel kiln with longitudinally extending masonry benches, at the sides of a pathway at the bottom of the kiln for goods carrying means and having mounted on each of said benches an elongated combustion chamber, pipes connected to and forming an extension of said combustion chamber, and a header to which the ends of the pipes remote from said combustion chamber are connected, each bench being 10 formed with a channel having uprising end portions which communicate one with the interior of said header and the other with the interior of the combustion chamber at
- the opposite ends of said pipes and with an outlet from said channel for products of combustion, and dampers regulating the relative amounts of products of combustion passing from the combustion chamber to said outlet through said pipes and a portion of said channel and through the bypass about said pipes formed by the remaining portion of said channel, the body portion of each of said channels being formed of tubular tile sections jointed together and embedded in concrete, each tubular tile sec- 15 tion being longitudinally split at one side.
- Signed at Pittsburgh in the county of Allegheny and State of Pennsylvania this 23rd day of January A. D. 1920.

ARTHUR C. SHEPARD.
